TRIPLE-ACTION PRESS

Rudolph W. Glasner, Chicago, and Einar K. Johansen, Oak Park, Ill., assignors to Clearing Machine Corporation, Chicago, Ill., a corporation of Illinois

Application January 20, 1950, Serial No. 139,617

6 Claims. (Cl. 113—38)

1

This invention relates in general to presses of the type for forming, shaping or drawing sheet metal, and particularly to mechanically operated presses for performing such functions. More specifically, the invention relates to mechanically operated presses of the so-called triple action type, as distinguished from the double action type disclosed in the copending application of Glasner and Johansen, Serial No. 122,208, filed October 19, 1949.

Mechanically operated metal drawing presses of the triple action type as presently used employ an outer or clamping slide which clamps a sheet metal blank or workpiece, and upper and lower draw slides. The upper or primary draw slide moves within the outer or clamping slide and performs the first drawing or shaping action on the sheet metal blank after it has been clamped into position by the outer or clamping slide. The lower or secondary draw slide is positioned below the sheet metal blank and is moved upwardly to perform a second drawing or shaping action on the blank after the upper draw slide has acted thereon. In some instances the parts may be reversed so that the lower slide acts first, in which case it becomes the first action slide. In any event the slide which performs the first draw is herein referred to as the primary slide, and the slide which performs the second draw is herein referred to as the secondary slide.

These present presses have proven very satisfactory in general, but they have the disadvantage in that they are unable to produce the desired production quantity principally because the number of operating cycles per period of time is limited. The inadequacy of the number of operations or operating cycles per period of time retards the production line and, therefore, limits and prevents rapid production. The reasons for the lack of more rapid production because of the limited number of cycles of operation within a given time limit are due to the construction, position and arrangement of parts. These prior mechanical presses are ordinarily operated by a linkage arrangement connected with the upper or primary draw slide and the lower or secondary draw slide is operated by a crank or eccentric arrangement connected therewith. In some cases the secondary draw slide is driven by a separate and independent drive means, and the forming or drawing of the sheet metal must be consistent with the type of sheet metal which is now available.

The present available sheet steel ordinarily has a safe maximum drawing or flowing speed of

about 60 feet per minute. Therefore, the actual speed at which sheet steel may be drawn is limited by the safe maximum permissible flowing or draw speed of the metal. Should the speed at which the metal is drawn be increased above this upper limit, the sheet metal will fracture, break or otherwise prevent a proper metal draw, unless the draw is relatively shallow.

Conventional mechanical crank operated metal presses therefore have the disadvantage in that the throw of the crank determines the depth of the draw of the primary draw slide or, conversely, the depth of the draw to be performed on the metal determines the throw of the crank to be used. For example, should a metal draw of 24 inches be required, the vertical movement of the upper draw slide must be at least 48 inches plus an additional amount to permit the finished drawn metal or article to be withdrawn from the dies. The primary draw slide must move 24 inches from the point it first engages the blank in order to finish the 24-inch draw. The draw slide must then be raised 24 inches to withdraw it from the finished piece where it will be at the same point where the metal drawing operation began. It is then necessary to raise the draw slide an additional 24 inches so that the finished or drawn article may be withdrawn from the press. Of course, there must be more than 48 inches over-all travel so that the finished drawn piece may be withdrawn freely from the press. In any event, the primary draw slide must have at least a 48-inch travel or movement for a 24-inch metal draw.

The crank which operates a draw slide to perform a 24-inch draw must necessarily have at least a 48-inch stroke, and inasmuch as the crank rotates and the crank connections operate in an arc, the actual peripheral length of the arc about which the crank connection travels, or the crank throw, will be the diameter of the arc times pi (4×3.1416), or approximately 12.5664 feet per minute. Since the drawing speed of sheet steel as used at the present time is about 60 feet per minute, the movement of the crank must be limited in speed according to the maximum permissible draw speed of the metal, viz. 60 feet per minute. Therefore to effect a 24-inch draw, the peripheral rotative speed of the crank will be 12.5664 feet per minute. Because the maximum metal drawing speed of the metal is limited to approximately 60 feet per minute, the number of cycles that the machine can perform with a crank of this given size is 60 divided by 12.5664

or slightly more than four and one-half (4.77) cycles per minute.

Being limited by the length or depth of the draw and the safe maximum speed at which metal may be drawn, the crank must be of a proportional size and therefore it is impossible to increase the production rate of the present crank-operated presses.

The present invention has to do with increased production on a triple action press of metal drawn articles without exceeding the actual and safe maximum drawing speed of the metal, the metal drawing operation still being limited by the conventional type of sheet steel available which has a safe maximum permissible drawing speed of approximately 60 feet per minute.

The primary object of the present invention, therefore, is to maintain the present drawing speed to which sheet steel is limited, but to provide a new system of operating mechanism in a triple action press to effect a greater number of cycles of operation over a given period of time.

A further object of the invention is the provision of new and improved mechanism for a triple action press whereby the operating mechanisms for all of the slides are interconnected and correlated to effect simultaneous travel of the clamping slide and primary draw slide to the point of clamping position of the clamping slide, then to maintain the outer or clamping slide in its clamping position while the primary draw slide is moved independently to effect the draw, then to cause the primary draw slide to dwell while the secondary draw slide effects its draw, thereafter to withdraw both the primary and secondary draw slides from operation, and finally to move the clamping and primary draw slides simultaneously to their original positions.

A further object of the invention is the provision of new and improved means for operating the primary draw slide and clamping slide as well as the secondary draw slide in a triple action press, the draw slides having a metal drawing speed not exceeding the maximum permissible drawing speed of the metal but operating to increase the number of operating cycles per minute over the conventional mechanically operated triple action presses.

A still further object of the invention is the provision of new and improved mechanism for operating a mechanical triple action press so as to increase the number of cycles of operation per minute for both the primary and secondary draw slides and still not exceed the maximum drawing speed of the metal blank, and so as to permit the bed of the press to be maintained at its usual lower position with the primary draw slide and clamping slide operating above the press bed, whereby the finished and completed or drawn article may be withdrawn from the press in the usual manner without inverting the dies.

A still further object of the invention is the provision of new and improved mechanism for operating the primary and secondary draw slides of a mechanical triple action press so as to increase the number of operating cycles per minute but reducing the usual effective vertical movement of the primary draw slide by eliminating the ordinary crank throw employed in connection with the conventional crank-operated draw slide and yet permit the primary draw slide to dwell while the secondary draw slide is performing its operation on the metal blank.

Still another object of the invention resides

in the arrangement of the mechanisms for operating both the primary and secondary draw slides and the clamping slide by the attachment of the slide operating mechanisms to a common movable member instead of attaching the mechanisms for the clamping and primary draw slides to a stationary cross head such as is usually employed and located in the crown of the press.

Another object of the invention resides in the provision of a plurality of interconnected, properly correlated and synchronized elements co-operating with both the clamping and primary draw slides to effect faster reciprocation of both slides simultaneously to a given point and then reducing the speed of the primary draw slide to effect the first drawing or forming operation in accordance with limits not to exceed the maximum permissible drawing speed of the metal being drawn, and thereafter causing a dwell of the primary draw slide while the secondary draw slide performs its drawing operation also at a speed not exceeding the actual drawing speed of the metal. Moreover there is provided a mechanical interlock between the connecting links for the clamping slide and the primary draw slide to permit a dwell of the primary draw slide at the proper time and prevent the slides from operating out of proper timed relationship with each other.

Other objects and advantages of the invention will become apparent from reading the following description taken in conjunction with the accompanying drawings, in which:

Fig. 1 is a detailed longitudinal vertical sectional view of the press of the present invention showing the clamping slide and the primary draw slide at their extreme upper positions and illustrating the secondary draw slide in its lowermost position, certain of the parts being broken away for the sake of clarity, and the linkage mechanism for actuating the primary draw slide being shown in elevation;

Fig. 2 is a view similar to Fig. 1 but showing the clamping slide in clamping position against the blank and the primary draw slide about to begin its drawing action, the secondary draw slide being shown in an intermediate position and the complete linkage mechanism for the clamping slide being shown in detailed elevation;

Fig. 3 is a view similar to Figs. 1 and 2 but showing the primary draw slide at the completion of its drawing action and the secondary draw slide about to begin its drawing operation, the linkage mechanism for the primary draw slide being shown in detailed elevation;

Fig. 4 is a vertical sectional view through the press showing the clamping slide and the primary draw slide still in position at the end of the first draw and showing the secondary draw slide at the completion of its drawing operation, the linkage mechanisms for the clamping slide and the primary draw slide being omitted from this view for the sake of clarity, and the crank construction together with the eccentric straps which operate the secondary draw slide being shown in detailed elevation;

Fig. 5 is a horizontal sectional view along the plane of line 5-5 of Fig. 1;

Fig. 6 is a fragmentary vertical sectional view taken along the plane of line 6-6 of Fig. 4;

Fig. 7 is a fragmentary detailed perspective view of interconnecting linkage between the clamping slide and the primary draw slide and illustrating the manner in which the clamping

slide mechanism and the primary draw slide mechanism are operatively connected or tied together;

Fig. 8 is a detailed horizontal sectional view taken along the plane of line 8—8 of Fig. 3;

Fig. 9 is a fragmentary vertical sectional view taken along the plane of line 9—9 of Fig. 2;

Fig. 10 is a fragmentary vertical sectional view taken along the plane of line 10—10 of Figs. 2 and 3;

Fig. 11 is a top plan view of the press;

Fig. 12 is a developed sectional plan view of the primary draw slide linkage, the linkage being spread out in a straight line to show the various linkage parts and the manner in which they are connected; and

Fig. 13 is a cyclograph of motion curve showing the operation of the three slides in the triple action press of the present invention.

The triple action mechanical press herein shown for the purpose of illustrating the present invention includes a main supporting structure generally indicated by the numeral 1. This supporting structure has as a part thereof a base or bed 2 reinforced by strengthening walls or webs 3 (Figs. 1 to 4). The press also includes an outer or clamping slide 4 and a primary draw slide 5 having a plurality of strengthening webs 6 integral therewith. At the bottom of the press there is provided a secondary draw slide 7 having a plurality of strengthening webs 8. The outer or clamping slide 4 at the upper part of the press is commonly called the first action slide since it is the first to move and perform its operation of clamping the metal blank in place to have the drawing operations performed thereon. The primary draw slide 5 may be referred to as the second action slide, since its drawing operation takes place immediately after the blank has been clamped in place, although it performs the first or primary drawing or forming action on the blank. The secondary draw slide 7 may be termed the third action slide, since it is the last to perform its drawing action on the metal blank.

A link 9 is connected to the outer or clamping slide at each corner of the press and is caused to reciprocate the clamping slide 4 at predetermined intervals by a suitable linkage mechanism to be described in more detail hereinafter. A link 10 is connected with the primary draw slide 5 at each corner of the press and causes reciprocation of the primary draw slide through the medium of a second linkage mechanism also to be described in more detail hereinafter. Eccentric straps or links 11 mounted on cranks are connected with the secondary draw slide 7 and cause operation of the secondary draw slide in a predetermined timed sequence with respect to the clamping and primary draw slides.

Referring now more particularly to Fig. 5, there is illustrated the manner in which a single motor is caused to actuate all three slides in the triple action press of the present invention. A main drive shaft 12 is supported in suitable bearings carried by a part of the main supporting structure 1. This main drive shaft 12 is driven in any suitable manner such as by belts 13 trained over a pulley 14 on the shaft 12 and over a pulley 15 on the motor shaft 16 of an electric motor 17.

The main drive shaft 12 carries a gear 18 which meshes with and drives a gear 19 on a transverse driven shaft 20, this shaft 20 being journaled in suitable bearings in the walls of the main frame.

The gear 19 also meshes with a similar gear 21 on a second drive shaft 22 also extending transversely of the machine and parallel with the driven shaft 20. Similar gears 23 and 24 are in mesh at the opposite side of the press and are mounted on the respective driven shafts 20 and 22. Drive gears 25, 26, 27, 28, 29 and 30 are fixed to the rotatable driven shaft 20. Similar drive gears 31, 32, 33, 34, 35 and 36 are mounted on the driven shaft 22. Rotation of the motor shaft 16 therefore causes the driven shafts 20 and 22, together with the gears mounted thereon, to rotate simultaneously, but in opposite directions, the shaft 20 and gears 19 and 23 at the ends thereof rotating in a clockwise direction and the shaft 22 with its gears 21 and 24 rotating in a counterclockwise direction as shown by the directional arrows, for example, in Fig. 2. A main split shaft 37 is suitably mounted within the frame of the machine in close relation to and parallel with the driven shaft 20. As will be presently seen, the shaft 37 is split to accommodate a crank at the center of the press to actuate the secondary draw slide. This split shaft 37 has clamping slide bull gears 38 and 39 mounted near the ends of the shaft, and these bull gears mesh with the gears 25 and 30, respectively, on the driven shaft 20. The shaft 20 and gears connected thereto, when driven in a clockwise direction, will thereupon rotate the bull gears 38 and 39 on the main shaft 37 in a counterclockwise direction.

A second main split shaft 40 at the opposite side of the machine is located adjacent the driven shaft 22 and is parallel therewith. Fig. 5 illustrates the mounting for the split shaft 40 to accommodate the crank for the secondary draw slide, this construction being identical with that for the main shaft 37 at the opposite side of the machine. The split main shaft 40, which is stationary, carries rotatably mounted outer slide bull gears 41 and 42 which are located near the outer ends of the shaft and which mesh respectively with the gears 31 and 36 on the driven shaft 22. The shaft 22, being driven in a counterclockwise direction, will rotate the gears 41 and 42 in a clockwise direction.

The outer slide bull gears 38 and 39 on the main split shaft 37 have outer slide eccentrics 43 and 44, respectively, which are rotatably mounted on the shaft 37. The bull gears 41 and 42 on the second main split shaft 40 carry eccentrics 45 and 46, respectively, which are rotatably mounted on the shaft 40. The eccentrics 43, 44, 45 and 46 carry eccentric straps 47, 48, 49 and 50 respectively which operate certain clamping slide linkage mechanisms 51 (Fig. 2) for the clamping slide connection links 9 of the outer or clamping slide 4. There is one such clamping slide linkage mechanism 51 and one such clamping slide connection link 9 at each of the four corners of the press, making a total of four such clamping slide linkage mechanisms 51 and four such clamping slide connection links 9 to reciprocate the outer or clamping slide 4 vertically in the main machine frame 1.

The main split shaft 37 has primary draw slide bull gears 52 and 53 rotatably mounted thereon between the outer slide gears 38 and 39. The gears 52 and 53 mesh with gears 26 and 29 respectively on the driven shaft 20 and are driven thereby in a counterclockwise direction.

The main split shaft 40 carries rotatably mounted primary draw slide bull gears 54 and 55 which are positioned between the outer slide gears 41 and 42. These gears 54 and 55 mesh

with gears 32 and 35 respectively on the driven shaft 22 and are driven thereby in a clockwise direction.

The bull gears 52 and 53 on the main split shaft 37 and the bull gears 54 and 55 on the split shaft 40 drive eccentrics 56, 57, 58 and 59 respectively which are rotatably mounted on the respective main shafts 37 and 40. The eccentrics 56, 57, 58 and 59 drive eccentric straps 60, 61, 62 and 63 respectively which operate certain primary draw slide linkage mechanisms 64 (Fig. 1) for the primary draw slide connection links 10 of the primary draw slide 5. There is one such primary draw slide linkage mechanism 64 and one such primary draw slide connection link 10 at each of the four corners of the upper draw slide, making a total of four such upper draw slide linkage mechanisms 64 and four such primary draw slide connection links 10 to reciprocate the primary draw slide 5 vertically in the main frame 1.

The main split shaft 37 also has secondary draw slide bull gears 65 and 66 rotatably mounted thereon at the inner ends of the split portions thereof. These gears 65 and 66 are connected together by a crank pin 67. The gears 65 and 66 mesh with gears 27 and 28 on the driven shaft 20 and are therefore driven in a counterclockwise direction. The split portions of main shaft 40 have secondary draw slide bull gears 68 and 69 rotatably mounted thereon, these gears 68 and 69 being connected together by a crank pin 70. These gears 68 and 69 mesh with gears 33 and 34 respectively on the driven shaft 22, whereby the gears 68 and 69 may be caused to rotate in a clockwise direction. The crank pins 67 and 70 carry the eccentric straps 11 and are connected at their upper ends to the secondary draw slide 7 (Figs. 1 to 5).

Outer or Clamping Slide 4 and Linkage Mechanism 51

The outer or clamping slide 4, as illustrated in Figs. 1, 2 and 3, is operated by certain linkage mechanism 51 which is clearly shown in Figs. 2 and 7. The operation of this linkage mechanism 51 causes a vertical reciprocation of the clamping slide connection links 9 to reciprocate the outer or clamping slide 4. Each linkage mechanism 51 (Figs. 2 and 7) for each link 9 comprises a bell crank 71 pivotally mounted on a stationary rocker pin or stud shaft 72. One end of the bell crank 71 is pivotally connected at 73 to a clamping slide eccentric strap, such as 50 and 48 in Fig. 2. The other end of bell crank 71 is pivotally connected at 74 to a link 75. The link 75 is pivoted at 76 to one arm of a bell crank 77 which is mounted on a stationary stud shaft 78. The other arm of bell crank 77 is pivotally connected at 79 to one end of a link 80. The other end of link 80 is pivotally connected at 81 to one arm of a bell crank 82. The bell crank 82 is pivotally mounted on a stationary shaft 83 and has the other arm thereof pivotally connected at 84 to one end of a connecting link 85. The other end of the connecting link 85 is pivotally connected at 86 to one arm of a bell crank 87 which is pivotally mounted on a stationary shaft 88 and rocks about this shaft 88. The other arm of bell crank 87 is pivotally connected to the lower end of a clamping slide connection link 9 by means of a clamping slide connection link pin 89 (Figs. 2 and 10). The upper end of each clamping slide connection link 9 is pivotally

mounted on a pivot pin 90 carried by the outer or clamping slide 4 (Figs. 2 and 9).

The linkage mechanisms 51 for each of the connecting links 9, from the point where the link 9 connects to the bell crank 87 up to the point 13 where the bell crank 71 pivotally connects to a clamping slide eccentric strap, are identical, there being a linkage mechanism 51 connected to each of the eccentric straps 41, 48, 49 and 50 to operate the respective clamping slide connecting links 9 (Fig. 5). The linkage mechanisms 51 are identical in construction, there being two such mechanisms on the right-hand side of the press and two such mechanisms 51 on the left-hand side of the press (Fig. 5). The positioning of the right and left-hand linkage mechanisms 51 is clearly shown in Fig. 2. These right and left-hand linkage mechanisms 51 are duplicated, there being one pair at the front of the press and one pair at the rear (Fig. 5). Since these linkage mechanisms 51 are all identical and since one of the mechanisms has been described in connection with one clamping slide connecting link 9, this description will suffice for the other linkage mechanisms 51 which operate the clamping slide connecting links 9.

Operation of the main drive shaft 12 rotates the driven shafts 20 and 22 through the medium of the gears 19 and 21 which, in turn, rotate gears 25 and 30 and their eccentrics 43 and 44 on the split shaft 37. The rotation of driven shaft 22 will also cause driven gears 31 and 36 to rotate on that shaft as well as gears 41 and 42 and their eccentrics 45 and 46 on split shaft 40. The eccentric straps 41, 48, 49 and 50, being connected through the linkage mechanisms 51 to the clamping slide connecting links 9, operate the bell cranks 71, links 75, bell cranks 77, links 88, bell cranks 82, links 85, and bell cranks 87. These bell cranks 87 are thereby caused to oscillate on their shafts 88. This oscillatory movement of the bell cranks 87 causes the connecting links 9, and consequently the clamping slide 4, to move vertically. This clamping slide 4 moves from the uppermost position shown in Fig. 1 to the clamping position shown in Figs. 2 and 3 and then back again to the original initial position shown in Fig. 1, whereby one full cycle of operation is completed.

Primary Draw Slide 5 and Linkage Mechanism 64

The eccentric straps 60 and 61 on shaft 37 and the eccentric straps 62 and 63 on shaft 40 operate the primary draw slide connecting links 10 to reciprocate the primary draw slide 5 in upward and downward directions (Figs. 1 and 3). The primary draw slide 5 is suitably guided in guides carried by the outer or clamping slide 4 and is adapted to reciprocate in and with respect to the outer or clamping slide. Each of the eccentric straps 60, 61, 62 and 63 operates a connecting link 10 through the medium of a primary draw slide linkage mechanism 64. There is a primary draw slide connection link 10 at each of the corners 65 of the primary draw slide and suitably attached thereto. Each linkage mechanism 64 which connects one of the eccentric straps to one of the primary draw slide links consists of a bell crank 91 rotatably mounted on a stud shaft 72. One arm of the bell crank 91 is pivotally connected at 93 to an eccentric strap such as 63 or 61 in Figs. 1 and 3. The other arm of bell crank 91 is pivotally connected at 94 to one end of a link 95. The other end of link 95 is pivotally connected at 96 to one arm of a bell crank 97 rotat-

ably mounted on a stud shaft 18. The other arm of bell crank 97 is pivotally connected at 99 to one end of a link 100. The other end of link 100 is pivotally connected at 101 to one arm of a bell crank lever 102 rotatably mounted on a stud shaft 83. The other arm of bell crank 102 is pivotally connected at 104 to one end of a link 105. The other end of link 105 is pivotally connected at 106 to one arm of a bell crank in the form of an arcuate member 107 pivotally mounted for rotation intermediate the ends thereof by the same pin 89 which connects the clamping slide connecting link 9 with the bell crank 87 of the clamping slide linkage mechanism. The other arm of bell crank 107 is pivotally connected at 108 to the lower end of a primary draw slide connecting link 10. The connecting link 10 is pivotally attached to the primary draw slide 5 at its upper end by means of a connecting pin 109 (Figs. 1, 3 and 9).

The primary draw slide linkage mechanism 64 for each primary draw slide connecting link 10, from the point where the lower end thereof pivotally connects with the bell crank 107 to the point 93 where the bell crank 91 connects with a corresponding primary draw slide eccentric strap, is identical, there being a linkage mechanism 64 connected to each eccentric strap 60, 61, 62 and 63 to operate a respective primary draw slide connecting link 10 (Figs. 1, 3 and 5). The linkage mechanisms 64 are identical in construction, there being two such linkage mechanisms 64 on the right-hand side of the press and two such linkage mechanisms on the left-hand side of the press (Fig. 5). These right- and left-hand primary draw slide linkage mechanisms 64 as shown in Figs. 1 and 3 are duplicated, there being a pair at the front and a pair at the rear, making a total of four such linkage mechanisms corresponding to the four eccentric straps 60, 61, 62 and 63 as shown in Fig. 5. The size, shape and construction as well as the pivotal connections for the various parts forming the linkage mechanisms 64, from the point 108 where the primary draw slide connecting links 10 connect with the bell crank 107 to the point 93 where the bell crank 91 pivotally connects with the eccentric strap, are identical; therefore, since the primary draw slide linkage mechanism has been described with respect to one primary draw slide connecting link 10, it is unnecessary to repeat the description with respect to the other linkage mechanisms for each of the other connecting links 10.

The rotation of the gears 52, 53, 54 and 55 and their eccentrics 56, 57, 58 and 59 on the respective shafts 37 and 40 will cause operation of all of the four primary draw slide linkage mechanisms 64. The primary draw slide mechanisms 64 operate the primary draw slide connecting links 10 which in turn cause vertical reciprocation of the primary draw slide 5.

Fig. 1 shows the primary draw slide 5 at its uppermost position. Fig. 2 shows the position of the primary draw slide just before the beginning of the metal drawing operation and at the time the clamping slide 4 is at its dwell and clamping position. Fig. 3 shows the primary draw slide 5 at the completion of its metal drawing operation. The primary draw slide 5 therefore is caused to reciprocate from the position shown in Fig. 1 to the position shown in Fig. 3 and then back to the position shown in Fig. 1 to complete one cycle of operation. The primary draw slide 5 and clamping slide 4 are driven by the driven shafts 28 and 22 whereby both the primary draw

slide and the clamping slide will operate together and in proper timed relation with each other. The construction, arrangement and operation of the linkage mechanism 51 for the clamping slide 4 and the linkage mechanism 64 for the primary draw slide 5 is such that both slides 4 and 5 will move downwardly from the initial upper positions shown in Fig. 1 to a position where the clamping slide 4 will clamp a workpiece 110 against a part of a lower female die 111 mounted on the press bed 2. The primary draw slide 5 carries a male forming die 112 which is adapted to cooperate with the female die 111 during the forming or drawing operation. The linkage mechanisms 51 and 64 are so constructed and arranged that there will be a dwell of the clamping slide 4 when the clamping slide clamping engages the metal blank 110 and during the time the primary draw slide 5 operates to perform the metal drawing operation. After the clamping slide has engaged and clamped the metal and while the clamping slide is dwelling, the primary draw slide continues downwardly to the position of Fig. 3 to effect the metal drawing operation.

Unlike the double action press, however, wherein the primary draw slide may begin its return upward movement immediately after the drawing operation, the triple action press of the present invention requires that the primary draw slide 5 dwell for a short period of time after its drawing operation to permit the secondary draw slide to perform its drawing operation on the metal blank. The necessity for this dwell of the primary draw slide 5 after its drawing operation requires a considerably different linkage mechanism arrangement for actuating the primary draw slide than would otherwise be necessary if the primary draw slide could return immediately after its drawing operation as in a double action press.

It is desirable and necessary that there be a proper dwell of the clamping slide 4 to permit the workpiece 110 to be securely and rigidly held in place on the lower die 111 while the metal drawing operation is being performed by both the primary and secondary draw slides. It is also necessary and desirable that the primary and secondary draw slides move away in their respective directions from the drawn metal before movement of the clamping slide 4 so as to free the dies and the finished article, whereupon the clamping slide and the primary draw slide move upwardly together while the secondary draw slide moves downwardly to permit the finished workpiece to be removed from between the dies.

The secondary draw slide 7

The secondary draw slide 7 has a forming die 113 mounted thereon. The actuating mechanism for the secondary draw slide 7 must be properly timed in synchronism with the operations of the clamping slide 4 and primary draw slide 5 so that the forming die 113 performs its drawing operation on the metal blank 110 immediately after the drawing operation of the primary draw slide 5 and during the dwell thereof. The gears 65 and 66 mounted on the inner ends of the split shaft 37 are connected by a crank 67 which has mounted thereon the eccentric strap 11. An identical strap 11 is mounted on the crank 70 which connects the two gears 68 and 69 at the opposite side of the machine on the shaft 40. Each eccentric strap 11 is pivotally connected by means of a

pin 11a on the secondary draw slide 7 (Figs. 1, 2, 3 and 6).

The gears 27 and 28 on the driven shaft 20 drive the gears 65 and 66 at the same rate of speed and in the same direction as the primary draw slide gears 52 and 53 and the outer slide gears 38 and 39. The crank 67 will cause eccentric movement of strap 11 in timed relation with the movement of the primary draw slide eccentric straps 60 and 61 and with the clamping slide eccentric straps 47 and 48. Likewise, the gears 33 and 34 on driven shaft 22 will drive gears 68 and 69 and crank 70 connected therebetween in the same direction and at the same rate of speed as the primary draw slide gears and eccentric straps 54, 55, 62 and 63, respectively, and as the clamping slide gears and eccentric straps 41, 42, 49 and 50, respectively.

The straps 11 are located on each side of the machine and move by means of the respective cranks 67 and 70 so as to reciprocate the secondary draw slide 7 upwardly and downwardly.

Bell crank construction for linkage mechanisms 51 and 64

The various bell cranks which are included in the clamping slide linkage mechanism 51 must be strong, durable and rigid, and must also be capable of withstanding hard usage and overcoming stresses and strains. This is also true for the bell cranks which effect operation of the primary draw slide 5. A practical arrangement for constructing these bell cranks is shown in Fig. 7.

The bell crank 87 which has connected thereto the connecting link 9 for operating the clamping slide 4 is composed of two sets of spaced suitable shaped plates, one set being indicated by the numerals 114 and 115 and the other set being indicated by the numerals 116 and 117. These spaced plates 114, 115, 116 and 117 which are shaped to form bell cranks are integrally connected together by a central hollow hub 118. This hollow hub 118 is mounted on the stub shaft 88 for pivotal movement with respect thereto. The connecting link 9 which operates the clamping slide 4 is arranged between the spaced side plates 114 and 115 and is pivotally connected thereto by means of the pivot pin 89. The link or arm 85 is likewise arranged between the spaced plates 114 and 115 and is pivotally connected thereto by means of the pivot pin 86.

The bell cranks 82, 77 and 71 are all similarly constructed, the bell crank 82 consisting of the spaced properly shaped plates 119 and 120. These spaced plates 119 and 120 are integrally connected by the central hollow hub 121 which receives the stub shaft 83, thereby allowing the spaced plates forming the bell crank 82 to pivot thereon. Bell crank 77 consists of the spaced properly shaped plates 122 and 123 integrally connected together by the hollow hub 124 which receives the stub shaft 78 and thereby allows the bell crank 77 to have pivotal movement thereon. Bell crank 71 embodies the spaced suitably shaped plates 125 and 126 integrally connected by the hollow hub 127 which receives the shaft 72 and permits the bell crank 71 to have pivotal movement thereon.

The eccentric strap 50 is received at one end thereof between the spaced plates 125 and 126 and is pivotally connected thereto by pivot pin 73. The intermediate links 75, 80 and 85 are all received between the spaced plates of the adjacent bell cranks and are pivotally connected thereto by the pivot pins as clearly shown in Fig. 7. Operation of the driving gear 42 (Figs. 2 and

5) will drive the eccentric strap 50 to reciprocate bell crank 87 about shaft 88 as a pivot through the medium of the linkage mechanism 51.

As previously pointed out, there are four such linkage mechanisms 51 to operate each of the four connecting links 9 for reciprocating the clamping slide 4. The bell cranks just described are identical in construction for each of the four sets of linkage mechanisms 51.

The arcuate bell crank 107 associated with each of the four linkage mechanisms 64 is also clearly illustrated in Fig. 7 and embodies the two spaced suitably shaped plates 128 and 129. These plates 128 and 129 are provided with inwardly extending bosses 130 and 131 (Fig. 8) which form spacing members to insure proper spacement of the plates. Each bell crank 107 embodying the spaced plates 128 and 129 is mounted for pivotal movement on the stub shaft 89 and between the spaced plates 116 and 117 on the bell crank 87. Thus it will be seen that rotation of bell crank 87 on the clamping slide 4 will include a rotation of the spaced plates 116 and 117 connected to the bell crank 107, whereupon suitable movement will be imparted to bell crank 107 independently of the eccentric strap associated with the primary draw slide linkage mechanism 64.

The other bell cranks 102, 97 and 91 comprising the linkage mechanism 64 are all similarly constructed and consist of spaced suitably shaped plates, the bell crank 102 being shown clearly in Fig. 7. The bell crank 102 includes the spaced plates 132 and 133 integrally connected by the hollow hub 134 which receives the stub shaft 83 on which the bell crank 82 of the clamping slide linkage mechanism is also mounted.

The connecting link 10 for the primary draw slide 5 has its lower end arranged between the spaced plates 128 and 129 of bell crank 107 and is connected thereto by the pivot pin 108. The link 105 has one end thereof received between the opposite ends of the spaced plates 128 and 129 and its other end received between the spaced plates 132 and 133 of bell crank 102.

The other bell cranks 97 and 91 are also formed of spaced suitably shaped plates in the same manner as bell crank 102 and receive the links 100 and 95 therebetween. Bell crank 97 of the primary draw slide linkage mechanism 64 is mounted for pivotal movement on shaft 78 which is the same shaft on which bell crank 77 of the clamping slide linkage mechanism 51 is mounted. Bell crank 91 of the primary draw slide linkage mechanism 64 is mounted for pivotal movement on shaft 72 which is the same shaft on which bell crank 71 of the clamping slide linkage mechanism 51 is mounted. The eccentric straps 60, 61, 62 and 63 have their outer ends each received between the spaced plates of the adjacent bell crank 91. Each eccentric strap connected to a bell crank 91 operates the linkage mechanism of the primary draw slide in such a way as to cause the drawing action of this slide and then to permit a dwell of the primary draw slide while the secondary draw slide performs its drawing operation upon the workpiece.

The various bell cranks of the primary draw slide linkage mechanism are arranged and interconnected with the bell crank 87 of the clamping slide linkage mechanism so that when the primary draw slide and clamping slide are both in their uppermost positions, as shown in Fig. 1, and then begin their respective downward movements, they will move downwardly together. At this point of initial downward movement, the

eccentric straps 60, 61, 62 and 63 have such slight movement that the linkage mechanism 64 will not be caused to move thereby. The eccentric straps 47, 48, 49 and 50 which actuate the clamping slide linkage mechanism 51 will then cause rotation of bell cranks 87 to move the connecting links 9 rapidly downwardly. At the same time, downward movement of the spaced plates 116 and 117 (Fig. 7) will move each bell crank 107 downwardly to effect rapid downward movement of the primary draw slide 5 through the connecting link 10. After the clamping slide has securely clamped the workpiece in position, then the eccentric straps 60, 61, 62 and 63 which operate the primary draw slide linkage mechanism 64 cause continued movement of bell cranks 107 while bell cranks 87 dwell. This action continues the downward movement of each connecting link 10, thereby causing the primary draw slide 5 to effect its drawing action. The arrangement of the bell cranks in each linkage mechanism 64 for the primary draw slide 5 is so arranged that after the drawing action has been completed, the primary draw slide will dwell during the work or drawing stroke of the secondary draw slide 1.

The eccentric straps 11, which are mounted on the cranks 67 and 70 and are driven by gears mounted on the split shafts 40, are connected directly to the secondary draw slide without any linkage mechanism intervening. This construction permits the secondary draw slide to be elevated and lowered quickly while both the clamping slide and the primary draw slide are dwelling. The eccentric straps 11 are so arranged on their respective shafts so as to begin upward movement while the clamping slide and primary draw slide are moving downwardly. At the end of the working stroke of the primary draw slide, the secondary draw slide will then be in position to begin its working stroke upwardly. The secondary draw slide then effects its drawing operation and immediately moves downwardly. After the secondary draw slide has begun its downward movement, the primary draw slide and clamping slide will move upwardly and will return to their uppermost positions shown in Fig. 1. At the conclusion of the upward travel of the clamping slide and primary draw slide and of the downward travel of the secondary draw slide, a new metal blank 110 is inserted in position and another cycle of operation is repeated.

It has been found that the construction employed in the slide operating mechanisms embodied in the present invention will permit a considerable number of cycles of operation to be performed within a given period of time. The number of actual operating cycles per unit of time is considerably greater than is possible with mechanical triple action presses employing the crank construction as commonly used. This is true even though the primary and secondary draw slides do not perform the actual drawing operation of the metal at any increased speed. The increased number of cycles is obtained by simultaneously and rapidly moving the clamping slide and primary draw slide whenever the primary and secondary draw slides are not effecting their respective drawing actions. Such operation is possible because the respective pairs of linkage mechanisms 51 and 64 are tied together or interconnected and because these linkage mechanisms are designed in a manner such that they will cause the clamping and primary draw slides to move relatively rapidly toward

and away from the workpiece whenever the latter is not being drawn by the primary and secondary draw slides. The clamping slide is positioned slightly below the primary draw slide in their uppermost positions so that as these slides move downwardly together, the clamping slide will contact the workpiece first and perform its clamping function thereon just before the primary draw slide contacts the workpiece and begins its drawing operation.

The secondary draw slide in conventional triple action presses does not ordinarily begin its upward movement until the work has been clamped in place by the clamping slide. This requires considerable dwell by both the clamping slide and the primary draw slide which is time consuming and is avoided in the present invention where the secondary draw slide begins its upward movement at substantially the same time that the clamping and primary draw slides begin their downward movement.

This increase of the number of cycles per given period of time is possible in the present invention by the arrangement of the linkage mechanisms which operate the slides and the manner in which they are tied together as heretofore explained.

It should be brought out that in the conventional triple action press, for a drawing depth of the primary draw slide of 24 inches, there must be an overall travel of the crank of more than 4 feet, because the primary draw slide must move downwardly 2 feet to perform the drawing operation and then move more than 4 feet upwardly to permit the completed work to be withdrawn from between the dies. For a 4-foot overall movement, there would have to be a peripheral movement of the crank of 4 times pi, which would be a total peripheral movement of 12.5664 feet. Inasmuch as the maximum drawing speed of the present conventional sheet steel now normally used is 60 feet per minute, there could be only about 4.77 cycles of operation per minute. Should the speed of operation of an ordinary crank operating the slides of a mechanical triple action press be increased, it would exceed the metal flowing or drawing action of the sheet steel. This increased speed would cause the sheet steel to rupture, crank or otherwise become deformed. In any event, the speed of the draw may never exceed the drawing capabilities of the metal which is approximately 60 feet per minute, the elasticity and other characteristics of the sheet metal being limited. The present construction permits the number of complete cycles of operation to be increased because the speed of travel of both the clamping slide and the primary draw slide, and also the speed of travel of the secondary draw slide, can be increased without exceeding the draw limit of the metal to be formed. The invention therefore permits the metal to be drawn at the proper speed, but allows the number of cycles per minute of the machine to be increased over that number permissible in conventional presses. A press embodying the present design and construction can almost double the output or production over present mechanical crank-operated triple action presses.

Fig. 13 is a cyclograph or a motion curve illustrating the timing and operation of the three slides. The curve indicated by the numeral 4 represents the motion curve of the clamping slide 4. The curve indicated at 5 represents the

motion of the primary draw slide 5, and the numeral 7 indicates the motion curve for the secondary draw slide 7. It will be noted that the clamping slide 4 and primary draw slide 5 move downwardly simultaneously, but the primary draw slide 5 moves downwardly at a greater rate of speed than the clamping slide 4. This results in the clamping action of the clamping slide 4 taking place only a fraction of a second before the primary draw slide begins its drawing operation as indicated by the point A in Fig. 13. The secondary draw slide 7 moves upwardly at the same time that the downward movement of the clamping slide 4 and primary draw slide 5 takes place. The secondary draw slide 7 begins its drawing operation at substantially the moment the primary draw slide 5 finishes its drawing operation at the point B in Fig. 13. The secondary draw slide 7 begins its return downward movement immediately after effecting the draw. During the drawing action of the secondary draw slide, the clamping slide 4 dwells during the cycle from point A to point C. During this action of the secondary slide 7, the primary draw slide also dwells from point B to point D. As soon as the secondary draw slide 7 has returned downwardly the distance of the draw, the primary draw slide 5 will begin its upward movement and a fraction of a second thereafter the clamping slide 4 begins its upward movement.

It will thus be evident that while the actual drawing operation of the draw slides consumes about the same length of time as is customary in conventional mechanical triple action presses, the movement of all of the slides before and after the drawing operation is much faster, whereby all of the slides are caused to return to their respective upper and lower open positions and thereafter return to the operating positions thereof in considerably less time than is ordinarily required in the usual mechanical triple action press. This motion curve establishes that the drawing operation is accomplished within the limits of the drawing capabilities of the metal, but the number of cycles of operation per minute is considerably increased over the number possible in conventional triple action presses.

Guides for clamping slide 4

The clamping slide 4 is guided for vertical reciprocation in the main frame or supporting structure 1. The main frame 1 is provided with guide members 135 at the four corners thereof, as clearly shown in Fig. 11. Each guide member 135 is rigidly and adjustably secured to a part of the main frame 1 and includes an inwardly extending leg 136 terminating in an inner inclined face 137. The face 137 of each guide member 135 is adapted to cooperate with an inclined face 138 on a projection 139 on the cross members 140 of the clamping slide 4. The cooperating and aligned faces 137 and 138 on the members 136 and 139, respectively, prevent shifting of the clamping slide 4 within the main frame 1 and maintain the outer or clamping slide in proper vertical sliding position with respect to the main frame 1. The guide faces 137 on the members 136 and the guide faces 138 on the members 139 of the clamping slide preferably extend from the top to the bottom of the main frame 1 and the clamping slide 4, respectively. The clamping slide 4 is therefore properly guided within the frame 1 of the press.

Guides for primary draw slide 5

The primary draw slide 5 is mounted within the confines of the clamping slide 4. The clamping slide is provided with a central opening 141 through which the primary draw slide 5 operates.

The primary draw slide 5 is guided by cooperating guides on the primary draw slide and the clamping slide. End shifting of the primary draw slide with respect to the clamping slide is prevented by the abutting engagement of guide strips or slides 142 and 143 on the primary draw slide and clamping slide, respectively, at both ends thereof. Front-to-rear shifting of the primary draw slide with respect to the clamping slide is prevented by the guides 139 on the clamping slide which terminate in guiding faces 144 engaging guide strips 145 on the primary draw slide, four such pairs of guiding members 144 and 145 being provided, there being two pairs of guides at the rear and two pairs of guides at the front, all as clearly shown in Fig. 11. The primary draw slide therefore is guided within the clamping slide by the cooperating engagement of the members 142 and 143 and the members 144 and 145. These guides preferably extend throughout the entire length of both slides so as to guide effectively both slides throughout the entire movement of the primary draw slide.

Adjustments for primary draw slide and clamping slide

The primary draw slide and the clamping slide are adapted to be shifted closer to or farther away from the lower die 111, which is mounted on the bed of the press according to the movement these slides are to have with respect to the particular drawing or metal forming operation. The primary draw slide and clamping slide may each be automatically adjusted according to the character of work being drawn and the depth of the drawing. The adjustment of each of the slides is accomplished by shifting the slides vertically with respect to the slide connection links 9 and 10. The primary draw slide 5 is adapted to be adjusted vertically by an electric motor 146 mounted on an upper surface of the primary draw slide 5. The shaft of the motor 146 carries a pinion 146a which engages a gear 147 on a drive shaft 148 (Fig. 11). This drive shaft 148 carries a drive gear 149 at each end thereof and these gears 149 mesh with gears 150 spaced on opposite sides of each of the gears 149. The gears 150 are each fixed to a shaft which carries and drives a bevel gear 151, there being a bevel gear 151 for each of the primary draw slide connecting links 10 (Figs. 9 and 11). Each of the bevel gears 151 meshes with a bevel gear 152. Each bevel gear 152 is fixedly secured to a nut 153 (Fig. 9) which is held against vertical movement by a retaining member 154. The gear 152 and nut 153 are, however, free to rotate. The nut 153 is threadedly engaged with the threads on an adjusting screw 155. Each adjusting screw 155 is provided with spaced jaws 156 at its lower end, which jaws receive the upper end of a connecting link 10. The pin 109 passes through the upper end of each connecting link 10 and through the spaced jaws 156, thereby securing the adjusting screw 155 to its adjacent connecting link 10. Therefore as the shaft of the motor 146 rotates, the bevel gears 152 and their companion nuts 153 will also rotate, but inasmuch as vertical movement of the nuts 153 is prevented by the retaining members 154 fixed to the top of the primary draw slide 5, the adjusting screw 155 will be trans-

lated vertically and cause the primary draw slide 5 to be translated downwardly or upwardly, depending upon the direction of rotation of the nuts 153. The four bevel gears 152 are all rotated at the same time during the rotation of shaft 148 by means of the motor 146. Therefore the same amount of movement will be effected with regard to each of the connecting links 10 whereby the primary draw slide will be translated vertically.

The means for effecting the vertical adjustment of the clamping slide 4 is accomplished in the same manner as the primary draw slide adjustment. Such means for effecting the clamping slide adjustment comprises worm gears 157 (Figs. 9 and 11) which also carry nuts 158 fixed to the top of the clamping slide by retaining members 159. Adjustment screws 160 threadedly engage each nut 158. Each of these screws 160 is connected to a link 9 by means of a pin 90 passing through the lower bifurcated end of screw 160 and through an opening in the upper end of link 9. Each worm gear 157 is driven by a worm 162 mounted on a shaft 163. The inner end of each shaft 163 carries a pinion 164 in mesh with a gear 165 on a shaft 166. There is one shaft 166 at each side of the machine and each such shaft carries a gear 165 on each end thereof. Thus there are four such gears 165 each meshing with a gear 164 driven by a shaft 163.

The opposite end of each shaft 163 carries a bevel gear 167 in mesh with another bevel gear 168 at each end of a transverse shaft 169. There is a transverse shaft 169 at each end of the machine which has mounted thereon at each end a bevel gear 168. Therefore there are four such bevel gears 168 each meshing with a bevel gear 167 on the outer end of a shaft 163. At one end of the machine one of the shafts 169 carries a gear 170 driven by a pinion on the motor shaft of motor 171. Operation of the motor 171 therefore causes each worm 162 to drive each worm gear 157 rotating the nut 158 and causing upward or downward shifting movement of each of the screws 160 and the clamping slide 4 through the connecting links 9 carried thereby. The operation of all of the gears being from the single motor 171 will cause the gears to be rotated exactly the same amount thereby causing all parts of the clamping slide to be moved upwardly or downwardly the same distance and at the same rate.

The secondary draw slide 7 needs no such adjusting mechanism associated therewith because the length of draw of the secondary draw slide can be adjusted by the size and shape of the die thereon or by shimming or building up the bottom of the die.

Any suitable clutch mechanism may be employed between the motor 17 and main drive shaft shown in Fig. 5. Only a single clutch is required or necessary to cause the clamping slide and both the primary and secondary draw slides to be operated from a single source of power which is the main drive motor 17. Separate clutches for the separate slides therefore are unnecessary, there being but one motor and one clutch provided for operating and controlling the operation of all three slides and the mechanism which operates them.

Résumé

The invention provides a mechanically operated press particularly of the triple action type in which is embodied a clamping slide, a primary draw slide and a secondary draw slide. Linkage mechanisms are provided in the press for first

moving the clamping slide into clamping engagement with a metal blank or workpiece. Other linkage mechanisms are provided for moving the primary draw slide so as to draw part of the workpiece or blank into a female die while the said workpiece is being clamped against the die by means of the clamping slide. Eccentric straps are connected directly with the secondary draw slide and with a crank mechanism for causing a drawing operation to be performed on the workpiece or blank by the secondary draw slide after the primary draw slide has completed its operation. The linkage mechanisms for the clamping slide and primary draw slide are tied together in a manner such that the primary draw slide will move downwardly with the clamping slide until the clamping slide engages the metal blank or workpiece. The primary draw slides moves through a greater distance than the clamping slide, and the linkage mechanisms are tied together in such a way as to move the primary draw slide downwardly with the clamping slide but more rapidly than the clamping slide so that the drawing operation of the primary draw slide will commence at substantially the moment the clamping slide is in clamping position. The linkage mechanisms for the primary draw slide operate to cause a drawing operation to be performed on the metal workpiece while the linkage mechanisms for the clamping slide cause said clamping slide to dwell in clamping position against the workpiece or blank.

The resulting increased production without increasing the drawing speed of the primary and secondary draw slides is obtained through the linkage mechanisms of the primary draw slide and the clamping slide plus the manner in which these linkage mechanisms are tied together. The clamping slide is caused to reciprocate by the linkage mechanisms 51. The primary draw slide is caused to reciprocate independently of the clamping slide by means of the linkage mechanisms 64. Each pin 89 (Figs. 1 and 2) connects the linkage mechanism 64 with the linkage mechanism 51 so that rotation of bell crank 87 will cause reciprocation of both the clamping slide 4 and primary draw slide 5 simultaneously. The additional rotation of bell crank 107 during this movement of bell crank 87 also causes reciprocation of the primary draw slide 5 thereby increasing the speed of the movement of the primary draw slide 5 at all times other than during the actual drawing operation. The linkage mechanism 64 is so arranged that the primary draw slide 5 is caused to dwell during the drawing operation of the secondary draw slide 7.

Present triple action presses wherein the clamping slide and primary draw slide are operated by a crank cause these slides to reciprocate at substantially the same rate of speed during the non-drawing movement thereof as during the drawing operation. The speed of drawing can not be increased beyond the limit of the metal to be formed; therefore the increased speed of the slides both before and after the drawing operation due to the linkage mechanisms will result in less time consumed from the time the blank is inserted on the lower die until the finished article is removed from the machine.

The invention also provides new and novel adjustment mechanisms whereby the clamping slide and primary draw slide may be adjusted vertically and whereby these slides may be adjusted independently of each other. Such adjusting mechanisms are provided in the press of the pres-

ent invention for the purpose of setting or adjusting the relative positions of the primary draw slide and the clamping slide for various kinds of metal drawing operations.

It is desirable that the bed of the press and the forming die, as well as the linkage mechanisms which operate the slides, be located at or near the bottom of the press with the clamping slide and primary draw slide located at or near the top of the press. The invention, however, contemplates the reversal of these parts so that the stationary bed will be above the clamping slide and the secondary draw slide and the linkage mechanisms will be in the crown of the press.

The present invention has been illustrated herein so that the primary draw slide is the second action slide and the secondary draw slide is the third action slide. The invention, however, contemplates further that the linkage mechanisms be so arranged that the secondary draw slide be the second action slide and the primary draw slide be the third action slide.

Changes may be made in the form, construction and arrangement of parts from that disclosed herein without departing in any way from the spirit of the invention or sacrificing any of the attendant advantages thereof, provided, however, that such changes fall within the scope of the claims appended hereto.

The invention is hereby claimed as follows:

1. A mechanical press of the triple action type comprising a frame structure including a bed, a clamp slide, a primary draw slide, a secondary draw slide, a clamp slide eccentric, a primary draw slide eccentric and a secondary draw slide eccentric, all of said eccentrics being mounted on a common drive shaft, a bell crank pivotally mounted on the frame structure, a plurality of rocker arms pivotally mounted on the frame structure, a set of links interconnecting said rocker arms, said links and said rocker arms interconnecting the clamp slide eccentric with said bell crank, a clamp slide link connecting said bell crank with said clamp slide, said clamp slide eccentric, bell crank, rocker arms and links being so arranged and coordinated with respect to each other that operation of the clamp slide eccentric will bring the clamp slide to clamping position and then cause the clamp slide to dwell, a second bell crank pivotally mounted on the first said bell crank at a point thereon spaced from the pivot of said first bell crank to the frame structure, a second plurality of rocker arms pivotally mounted on the frame structure, a second set of links interconnecting said second plurality of rocker arms, said second plurality of rocker arms and said second set of links interconnecting the primary draw slide eccentric with one arm of said second bell crank, a draw slide link connecting the other arm of said second bell crank with said primary draw slide, said primary draw slide eccentric, second bell crank, and second plurality of rocker arms and links being so arranged and coordinated with respect to each other that operation of the primary draw slide eccentric will cause said primary draw slide to perform a drawing operation and then dwell, and means connecting said secondary draw slide eccentric with said secondary draw slide, said eccentrics being angularly offset from each other so that operation of the clamp slide eccentric will move both the clamp slide and the primary draw slide toward the bed bringing the clamp slide into clamping position, the effective operation of the primary draw slide eccentric to effect the drawing operation of the

primary draw slide eccentric to effect the drawing operation of the primary draw slide will occur during the dwell of the clamp slide, and so that the effective operation of the secondary draw slide eccentric to effect the drawing operation of the secondary draw slide will occur during the dwell of the clamp slide and the primary draw slide.

2. A mechanical press of the triple action type comprising a frame structure including a bed, a clamp slide, a primary draw slide, a secondary draw slide, a clamp slide eccentric, a primary draw slide eccentric and a secondary draw slide eccentric, all of said eccentrics being mounted on a common drive shaft, a rocker member pivotally mounted on the frame structure, a plurality of rocker arms pivotally mounted on the frame structure, a set of links interconnecting said rocker arms, said links and said rocker arms interconnecting the clamp slide eccentric with said rocker member, a clamp slide link connecting said rocker member with said clamp slide, said clamp slide eccentric, rocker member, rocker arms and links being so arranged and coordinated with respect to each other that operation of the clamp slide eccentric will bring the clamp slide to clamping position and then cause the clamp slide to dwell, a second rocker member pivotally mounted on the first said rocker member at a point thereon spaced from the pivot of said first rocker member to the frame structure, a second plurality of rocker arms pivotally mounted on the frame structure, a second set of links interconnecting said second plurality of rocker arms, said second plurality of rocker arms and said second set of links interconnecting the primary draw slide eccentric with said second rocker member, a draw slide link connecting said second rocker member with said primary draw slide, said primary draw slide eccentric, second rocker member, and second plurality of rocker arms and links being so arranged and coordinated with respect to each other that operation of the primary draw slide eccentric will cause said primary draw slide to perform a drawing operation and then dwell, and means connecting said secondary draw slide eccentric with said secondary draw slide, said eccentrics being angularly offset from each other so that operation of the clamp slide eccentric will move both the clamp slide and the primary draw slide toward the bed bringing the clamp slide into clamping position, the effective operation of the primary draw slide eccentric to effect the drawing operation of the primary draw slide will occur during the dwell of the clamp slide, and so that the effective operation of the secondary draw slide eccentric to effect the drawing operation of the secondary draw slide will occur during the dwell of the clamp slide and the primary draw slide.

3. A mechanical press of the triple action type comprising a frame structure including a bed, a clamp slide, a primary draw slide, a secondary draw slide, a clamp slide eccentric, a primary draw slide eccentric and a secondary draw slide eccentric, common drive means for all of said eccentrics, a rocker member pivotally mounted on the frame structure, a plurality of rocker arms pivotally mounted on the frame structure, a set of links interconnecting said rocker arms, said links and said rocker arms interconnecting the clamp slide eccentric with said rocker member, a clamp slide link connecting said rocker member with said clamp slide, said clamp slide eccentric, rocker member, rocker arms and links being so

arranged and coordinated with respect to each other that operation of the clamp slide eccentric will bring the clamp slide to clamping position and then cause the clamp slide to dwell, a second rocker member pivotally mounted on the first said rocker member at a point thereon spaced from the pivot of said first rocker member to the frame structure, a second plurality of rocker arms pivotally mounted on the frame structure, a second set of links interconnecting said second plurality of rocker arms, said second plurality of rocker arms and said second set of links interconnecting the primary draw slide eccentric with said second rocker member, a draw slide link connecting said second rocker member with said primary draw slide, said primary draw slide eccentric, second rocker member, and second plurality of rocker arms and links being so arranged and coordinated with respect to each other that operation of the primary draw slide eccentric will cause said primary draw slide to perform a drawing operation and then dwell, and means connecting said secondary draw slide eccentric with said secondary draw slide, said eccentrics being maintained in a predetermined angular relationship from each other so that operation of the clamp slide eccentric will move both the clamp slide and the primary draw slide toward the bed bringing the clamp slide into clamping position, the effective operation of the primary draw slide eccentric to effect the drawing operation of the primary draw slide will occur during the dwell of the clamp slide, and so that the effective operation of the secondary draw slide eccentric to effect the drawing operation of the secondary draw slide will occur during the dwell of the clamp slide and the primary draw slide.

4. A mechanical press of the triple action type comprising a frame structure including a bed, a clamp slide, a primary draw slide, a secondary draw slide, a clamp slide eccentric, a primary draw slide eccentric and a secondary draw slide eccentric, common drive means for all of said eccentrics, a rocker member pivotally mounted on the frame structure, linkage means interconnecting the clamp slide eccentric with said rocker member, at least one of the links in said linkage means being pivotally mounted on the frame structure, a clamp slide link interconnecting said rocker member with said clamp slide, said clamp slide eccentric, rocker member, linkage means and clamp slide link being so arranged and coordinated with respect to each other that operation of the clamp slide eccentric will bring the clamp slide to clamping position and then cause the clamp slide to dwell, a second rocker member pivotally mounted on the first said rocker member at a point thereon spaced from the pivot of said first rocker member to the frame structure, a second linkage means connecting said second rocker member to said primary draw slide eccentric, a draw slide link connecting said second rocker member with said primary draw slide, said primary draw slide eccentric, second rocker member, second linkage means and draw slide link being so arranged and coordinated with respect to each other that operation of the primary draw slide eccentric will cause said primary draw slide to perform a drawing operation and then dwell, and means connecting said secondary draw slide eccentric with said secondary draw slide, said eccentrics being maintained in a predetermined angular relationship from each other so that operation of the clamp slide eccentric will move both the clamp slide and the primary draw slide.

slide toward the bed bringing the clamp slide into clamping position, the effective operation of the primary draw slide eccentric to effect the drawing operation of the primary draw slide will occur during the dwell of the clamp slide, and so that the effective operation of the secondary draw slide eccentric to effect the drawing operation of the secondary draw slide will occur during the dwell of the clamp slide and the primary draw slide.

5. A mechanical press of the triple action type comprising a frame structure including a bed, a clamp slide, a primary draw slide, a secondary draw slide, a clamp slide eccentric, a primary draw slide eccentric and a secondary draw slide eccentric, common drive means for all of said eccentrics, a bell crank pivotally mounted on the frame structure, operating means connecting said clamp slide eccentric with said bell crank, a clamp slide link connecting said bell crank with said clamp slide, said clamp slide eccentric, bell crank, operating means and clamp slide link being so arranged and coordinated with respect to each other that operation of the clamp slide eccentric will bring the clamp slide to clamping position and then cause the clamp slide to dwell, a second bell crank pivotally mounted on the first said bell crank at a point thereon spaced from the pivot of said first bell crank to the frame structure, a second operating means connecting said second bell crank to said draw slide eccentric, a draw slide link connecting said second bell crank to said primary draw slide, said primary draw slide eccentric, second bell crank, second operating means and draw slide link being so arranged and coordinated with respect to each other that operation of the primary draw slide eccentric will cause said primary draw slide to perform a drawing operation and then dwell, and means connecting said secondary draw slide eccentric with said secondary draw slide, said eccentrics being maintained in a predetermined angular relationship from each other so that operation of the clamp slide eccentric will move both the clamp slide and the primary draw slide toward the bed bringing the clamp slide into clamping position, the effective operation of the primary draw slide eccentric to effect the drawing operation of the primary draw slide will occur during the dwell of the clamp slide, and so that the effective operation of the secondary draw slide eccentric to effect the drawing operation of the secondary draw slide will occur during the dwell of the clamp slide and the primary draw slide.
6. A mechanical press of the triple action type comprising a frame structure including a bed, a clamp slide, a primary draw slide, a secondary draw slide, a clamp slide eccentric, a primary draw slide eccentric and a secondary draw slide eccentric, drive means for all of said eccentrics, linkage means connecting said clamp slide eccentric with said clamp slide including a link pivotally mounted on the frame structure, and said linkage means being so arranged and coordinated that operation of the clamp slide eccentric will bring the clamp slide to clamping position and then cause the clamp slide to dwell, a second linkage means connecting said primary draw slide eccentric with said primary draw slide, including a link pivotally mounted on said first link at a point thereon spaced from the pivot of said first link on the frame structure, said second linkage means being so arranged and coordinated that operation of the primary draw slide eccentric will cause said primary draw slide to perform a draw-

ing operation and then dwell, the arrangement of said linkages being such that operation of the first said linkage means will operate said second linkage means for moving said draw slide, and means connecting said secondary draw slide eccentric with said secondary draw slide, said eccentrics being maintained in a predetermined angular relationship from each other so that the operation of the clamp slide eccentric will move both the clamp slide and the primary draw slide toward the bed bringing the clamp slide into clamping position, the effective operation of the primary draw slide eccentric to effect the drawing operation of the primary draw slide will occur during the dwell of the clamp slide, and so that the effective operation of the secondary draw slide eccentric to effect the drawing operation of

the secondary draw slide will occur during the dwell of the clamp slide and the primary draw slide.
